FLUID DISTRIBUTION SYSTEM

Donald G. Griswold, Alhambra, Calif., assignor
to Clayton Manufacturing Company, Alhambra,
Calif.

Application August 18, 1939, Serial No. 290,912

35 Claims.

(Cl. 161—7)

The present invention relates to a fluid distribution system of general utility, but which at the same time is especially adapted for sprinkling or watering lawns, irrigating orchards, etc.

More particularly, the invention relates to a fluid distribution system having a main supply pipe feeding a plurality of service pipes, and a master control device for controlling the flow through said service pipes and which control device may be located at a convenient point remote from the discharge of said service pipes. The system further includes a separate diaphragm valve in each service pipe line for controlling the flow therethrough. The master control device is arranged to control all of said valves simultaneously and in such manner that the valves open automatically one at a time in predetermined succession; each valve remaining open for a desired time interval.

In accordance with the present disclosure, a pressure-controlled diaphragm valve is connected in each of the service lines and the opening and closing of the diaphragm valves is controlled by a master control unit including a timing mechanism and a master pilot valve actuated by said timing mechanism for admitting pressure fluid to and exhausting pressure fluid from said diaphragm valves.

One of the important features of the invention is the provision of a control unit having but a single control knob adapted to be manually rotated one or more turns, the control unit being arranged so that flow will occur through each of the service pipes of the system when the control knob is given substantially one complete revolution; the flow through each service pipe continuing for a predetermined time interval and being repeated through the various service pipes, once for each additional turn given to the control knob. For example, if the control knob is rotated manually through substantially three complete revolutions, the flow through each service pipe will be repeated three times at predetermined intervals.

A system including five diaphragm valves has been shown to illustrate the broad principles of the invention. These valves will be referred to hereinafter as valves 1, 2, 3, 4 and 5. Obviously, a lesser or greater number of valves may be employed in practicing the invention.

The master control unit comprises a conventional clock mechanism including a main spring, which is wound by manually rotating the control knob in a clockwise direction, and a driven shaft which is actuated by the clock mechanism in a counter-clockwise direction upon unwinding of

the spring. The arrangement is such that the control knob is operatively connected with and rotated counter-clockwise along with the driven shaft until it is restored to its initial position.

5 Novel gearing may be associated with the driven shaft to limit the maximum number of turns which can be imparted thereto by the control knob. If desired, a stop pin may be used in lieu of the gearing in instances where a non-repeating system will suffice.

The driven shaft of the clock mechanism is connected to drive a shaft controlling a master pilot valve disc. The pilot disc is positioned in a chamber containing fluid under pressure and

15 is arranged and ported to permit opening of one diaphragm valve of the system to exhaust pressure fluid therefrom while maintaining pressure upon the remaining valves to maintain the same closed. The operation of the system is entirely open

20 automatic following the initial manual actuation of the control knob. Thus, the control unit automatically opens and closes the several diaphragm valves of the system to permit timed flow through the several pipe lines of the system successively, and repeats the flow, when desired, through said valves and their associated pipe lines as many times as desired.

Another feature of the invention is the provision of a diaphragm valve which can be adjusted 30 to vary the volume of flow, or to remain closed, independently of the master control unit, in order to vary or prevent flow through a given service pipe of the distribution system, as desired.

One of the principal objects of the invention 35 is to provide a fluid supply or distribution system and a control therefor which will produce successive flow through each service line and maintain such flow through each line for a predetermined period of time.

40 Another object of the invention is to provide a fluid supply or distribution system controlled so that the flow through the various service pipes thereof may be repeated a given number of times in order to deliver fluid at any points desired, at timed intervals.

A more specific but important object of the invention is to provide a fluid distribution system for sprinkling lawns, etc. which will provide for 50 substantially uniform watering and which obviates the local "soaking" or "starving" inherent in the manual sprinkling with a hose.

A further object of the invention is to provide a sprinkler system having automatically timed flow through the various service pipes and sprinkler heads thereof.

Still another object of the invention is to provide a sprinkler or watering system in which the flow through a given pipe line thereof may be repeated automatically at predetermined time intervals.

A still further object of the invention is to provide control means for fluid distribution systems which can be set, in the case of a sprinkler system, to repeat the flow or watering operation a desired number of times to meet climatic conditions.

Another object of the invention is to provide a spring-wound timing mechanism having a control knob and a driven shaft with means including novel gearing for limiting the number of turns through which said knob may be manually rotated to wind said spring.

A further object of the invention is to provide a control unit having a pilot-controlled master valve with a valve disc that can be rotated by relatively small actuating force.

A still further object of the invention is to provide, in a master control device, a pilot valve disc constructed so that a minimum valve seating surface is exposed to the action of corrosion, whereby the pilot disc will remain easily operable by a small force even after installed for a considerable period of time.

A still further object of the invention is to provide a pilot controlled master valve arranged so that the pilot will be operable or rotatable by a substantially constant force, irrespective of the pressure of the liquid controlled by said valve.

A still further object of the invention is to provide a control for a pilot operated master valve in the form of a manually windable clock mechanism arranged so that, upon rotation of the control knob for winding said clock mechanism, the master pilot valve disc will be rotated a number of turns corresponding to that given to said control knob and will be automatically returned upon release of the knob through a corresponding number of turns to its initial position.

Still another object of the invention is to provide a novel diaphragm valve with means which can be adjusted to vary the volume of flow through said valve or to completely cut off flow therethrough, as desired.

Another object of the invention is to provide a semi-automatic fluid distribution system which is relatively simple in construction, comparatively inexpensive, easy to install and operate, and which requires a minimum of care and attention upon the part of the user.

Other and further objects of the invention will be apparent from the following description, taken in conjunction with the accompanying drawings, in which:

Figure 1 is a view diagrammatically illustrating an embodiment of the invention in the form of a sprinkler system;

Figure 2 is a longitudinal sectional view of the master control unit for the system together with its associated tubes and piping;

Figure 2a illustrates certain modifications in the details of the control unit of Figure 2;

Figure 3 is a sectional plan view taken on the line 3-3 of Figure 2, showing the control knob of the main control unit and its cooperating indicator plate;

Figure 4 is a sectional view taken on the line 4-4 of Figure 2, showing in particular the porting of the seat for the pilot valve disc;

Figure 5 is a sectional view taken on the line 75

5-5 of Figure 2, showing the porting of the gasket that is interposed between the control housing and the bottom closure plate or head therefor;

5 Figure 6 is a sectional view taken on the line 6-6 of Figure 2, showing the arrangement of ports in, and the tubing connected with, said closure plate;

10 Figure 7 is an enlarged partial sectional view of the strainer plug of the control unit shown in Figure 2;

Figure 8 is a perspective view of the pilot valve disc and the driving member therefor;

15 Figure 9 is an enlarged sectional view through one form of novel gearing for limiting the number of turns which may be given to the control knob, a portion of the clock casing also being shown in section;

20 Figure 10 is a sectional view taken on the line 10-10 of Figure 9, showing a suitable gearing arrangement for permitting substantially three complete turns of the control knob, the gearing being illustrated in the "off" position of the control knob;

25 Figure 11 is a view similar to Figure 10 but showing the gearing after the control knob has been given substantially three complete turns to an "on" position;

30 Figure 12 shows a modified form of gearing permitting substantially one turn of the control knob;

Figure 13 illustrates a gearing arrangement permitting two turns of the control knob;

35 Figure 14 shows gearing similar to that of Figures 10 and 11 but with one of the gears rearranged to permit substantially four turns of the control knob;

40 Figure 15 illustrates a form of gearing similar to that shown in Figure 13 but with one of the gears rearranged to permit substantially five turns of control knob;

Figure 16 shows gearing similar to Figure 12 but with one of the gears rearranged to permit substantially six turns of the control knob;

45 Figure 17 is a schematic view illustrating the relative position of the control knob and the ports and grooves in the pilot valve disc and seat, respectively, when the distribution system is in its inoperative or "off" position;

50 Figure 18 is a view similar to Figure 17 but showing the relationship of the same parts after the control knob has been given substantially one or more complete turns in a clockwise direction and has returned in a counterclockwise direction to a position such that only diaphragm valve 1 is open;

55 Figure 19 is another similar view but showing the relative positions of the parts while valve 1 is still open and the pilot valve disc is being rotated to effect opening of valve 2 and the closing of valve 1;

Figure 20 is a longitudinal sectional view through one of the diaphragm valves of the present system;

60 65 Figure 21 is a plan view of the valve shown in Figure 20;

Figure 22 is a view of the upper portion of a control unit such as illustrated in Figure 2 but showing a modified form of control in which the gearing for limiting the turns of the control knob has been eliminated and a pin is employed to limit the turning of the control knob to substantially one revolution; and

Figure 23 is a sectional plan view taken on the line 23-23 of Figure 22.

Referring now to Figure 1 of the drawings, the reference numeral 6 generally indicates a main supply pipe or water main to which a series of branch conduits or service pipes 7 is connected. For convenience in illustration, five such service pipes have been shown. It will be understood, however, that any desirable number of service pipes may be employed and that such service pipes may be straight or curved, or branched in any desirable manner, in order to position suitable sprinkler heads 8 in any desired advantageous relationship. The distribution of fluid through the service pipes 7 is controlled by a master control unit C which regulates the opening and closing of diaphragm valves 1, 2, 3, 4 and 5, respectively, one such valve connected in each of said service pipes.

Pressure fluid for actuating the respective diaphragm valves is supplied to the master control unit C through a tube or conduit P connecting said unit with the main supply pipe 6. Communication between the master control unit C and the diaphragm valves 1, 2, 3, 4 and 5 is established by tubing 1a, 2a, 3a, 4a and 5a, respectively, connecting said control unit with said diaphragm valves. Each of said tubes is arranged to conduct operating pressure fluid to its associated diaphragm valve to maintain the same closed, and to exhaust pressure fluid therefrom to permit the same to open, as will be more fully explained hereinafter. Any spent pressure fluid returned from the diaphragm valves to the master control unit through said tubes is drained from said master control unit through a tube D, as will also be fully set out hereinafter. A bleeder tube B is also connected with the master control unit C for draining any pressure fluid which may escape from the pilot valve chamber of said control unit, as will be described hereinafter.

The details of the master control unit C are best shown in Figures 2 and 3. It will be clear from these figures that said unit comprises a main housing 10 and a hinged cap 11 pivotally mounted at one side thereof upon a pin 12 supported by ears 13 projecting laterally from said housing. The opposite side of the cap 11 is provided with a tongue 14 which extends downwardly between a pair of lugs 15 projecting outwardly from said housing. The tongue 14 is provided with an aperture 16 which is positioned below the lugs 15 when the cap is in closed position. The aperture 16 is thus adapted to receive a pin, lock, or other means for maintaining the cap in closed position, thereby preventing mischievous tampering with the control unit.

A clock mechanism generally designated 17 is received in a recess 18 at the upper end of the main housing 10 and is disposed between a horizontal shoulder 19 at the base of recess and a cover plate 20 closing the upper end of said recess. A gasket 21 is interposed between the cover plate 20 and a horizontal flange 22 projecting from the main housing. A series of screws 23 retain the cover plate 20, gasket 21 and the clock mechanism 17 in assembled relation with the housing 10.

The cover plate 20 is provided with an axially offset aperture 24 into which a hollow interiorly threaded bushing 25 is pressed. The bushing 25 is arranged to extend into a recess 26 formed in the upper wall of the casing of the clock mechanism 17, whereby to prevent relative rotation of said clock mechanism with respect to the cover plate and housing. The clock mechanism is preferably made oil- and water-tight so that 75

moisture cannot enter the casing of said clock mechanism and so that the mechanism within said casing may run in oil. In order to prevent the entrance of water into or the escape of oil from the clock casing, a somewhat flat-headed screw 27 is threaded into the bushing 25 to close the opening therein.

A control knob 30 is mounted upon one end 31 of a shaft 32 which extends into the casing of the clock mechanism 17. The shaft 32 is provided with a shoulder 33 against which a washer 34, arranged in the lower side of the control knob 30, is seated. The upper extremity of the shaft end 31 is threaded to receive a nut 35 for securing the control knob 30 in a desired adjusted position with respect to the shaft 32. Water is prevented from entering the recess 18 along the shaft 32 by a felt packing washer 36 and a stuffing box member 37.

20 The cover plate 20, as shown in Figure 3, is provided with suitable indicia for indicating, in cooperation with the control knob 30, whether the fluid distribution system is completely shut off, or whether flow is occurring through a given distribution diaphragm valve and its associated service pipe. Thus, the cover plate 20 is inscribed with a zero to indicate that there is no flow or, in other words, that the system is turned off. Suitably graduated and shaded areas 38 are 25 provided on the face of the cover plate for indicating, in cooperation with the control knob, whether flow is occurring through valves 1, 2, 3, 4 or 5 associated with the various service pipe lines 7.

30 35 The clock mechanism 17 is preferably of the spring type, whereby manual rotation of the control knob 30 will wind the main spring of said clock mechanism. One of the features of the invention is that the control unit provides for successive flow through all of the service pipes of the system when the control knob 30 is turned through substantially one complete revolution and that the flow is repeated for each turn of the control knob in excess of one. It may be desirable to limit the number of turns which may be given to the control knob and means to accomplish the same is shown herein in the form of suitable gearing associated with the driven shaft of the clock mechanism.

50 55 For illustrative purposes, a gearing arrangement has been shown in Figures 2, 9, 10 and 11 which is adapted to limit the maximum number of turns of the control knob 30 to three. However, it will be understood that said gearing may be rearranged to provide for a maximum of four turns as in Figure 14, or other suitable gearing may be substituted to obtain any desired number of maximum turns. It will also be understood that upon release of the control knob 30, the main 60 spring (not shown) in the clock mechanism will cause said control knob to slowly return to its initial position, rotating through identically the same number of turns imparted to the shaft 32 by manual winding of said knob. The spring may be of such character as to be wound by rotating the control knob 30 in a clockwise direction, in which event the return of the control knob in a counterclockwise direction will be effected by the clock mechanism.

65 70 The shaft 32, which is rotated by the control knob 30 to wind the clock mechanism and is in turn driven by said clock mechanism, has a drive member 40 pressed or otherwise secured to its lower end 41, as best shown in Figure 9. A gear

42 is fixedly secured to a hub portion 43 of said drive member 40. A plurality of pins 44 are carried by said drive member for driving the shaft of a master pilot valve disc as will be explained hereinafter. The gear 42 meshes with a gear 43 rotatably mounted upon the shank portion 45 of a screw 46. One end portion 47 of said shank is reduced and threaded into an opening 17a formed in the lower wall 17b of the casing of the clock mechanism 17.

The gears 42 and 43 are shown in detail in Figures 10 and 11. It will be observed that the gear 42 contains five symmetrically arranged teeth 48 and a sixth tooth 49 which is of greater radial length than the teeth 48. It will also be observed that the gear 43 has seven teeth 50 symmetrically arranged about its axis of rotation with deep spaces 51 between certain of the teeth and shallow spaces 52 and 52a between certain other of said teeth. The base of said shallow spaces is preferably flat, as shown at 53.

The spacing of the axes of rotation of the gears 42 and 43, and the length of the teeth 48, and the depth of the spaces 51, 52 and 52a is such that the teeth 48 may be received in any of said spaces without preventing relative rotation of said two gears. However, the length of tooth 49 and the depth of the spaces 51, 52 and 52a is such that said spaces 51 can readily receive said tooth without locking the gears 42 and 43 against rotation, but the shallow spaces 52 and 52a are such that when the tooth 49 lodges therein, the flat portion 53 of said shallow spaces engages the extremity of said tooth and positively locks the gears against rotation in one direction. The relative arrangement of the gears shown in Figure 10 is such that the shaft 32 may be manually rotated through the control knob 30 to turn the gear 42 through substantially three complete turns, or until the tooth 49 of gear 42 becomes lodged in the shallow recess 52a of the gear 43, as shown in Figure 11. The release of the control knob 30 will then permit the spring of the clock mechanism to rotate the shaft 32 and gear 42 in a counter-clockwise direction through the same number of turns previously imparted thereto by manual rotation of the control knob.

The gearing arrangement shown in Figures 10 and 11 limits the maximum number of turns which may be given to the control knob to three, but it is obvious that the operator may release the control knob 30 after having given it only a fraction of a turn, or one or two turns.

It will be evident from Figure 14 that the maximum number of turns which may be given to the control knob 30 may be increased to four simply by changing the initial position of the gear 43 relative to the gear 42. In other words, initially arranging the gears so that the flat portion of the shallow recess 52a engages the tooth 49 instead of the shallow recess 52.

Figure 12 shows a modified form of the gear 43 in which shallow recesses 52b and 52c are arranged adjacent each other. When the tooth 49 is engaged in the shallow space 52b, a maximum of one complete turn may be given to the shaft 32 by the control knob 30. This maximum number of turns may be increased merely by changing the relative initial position of the gears to the position shown in Figure 16, in which the tooth 49 is shown engaged in the shallow space 52c. Such arrangement will permit the gear 42 to be rotated substantially through six complete revolutions before the tooth 49 will engage

with the flat portion of the shallow space 52b.

Figure 13 illustrates a further modification of the gear 43 in which shallow spaces 52d and 52e are spaced apart by one relatively deep space 51a. With the gears arranged as shown, the control knob may be rotated through a maximum of about two turns before the tooth 49 will engage in the shallow space 52e.

Figure 15 illustrates a rearrangement of the gears shown in Figure 13 in which the tooth 49 is originally positioned in the recess 52e. Such arrangement permits the control knob 30 to rotate the gear 42 through approximately five complete turns before the tooth 49 will become lodged in the shallow space 52d.

The pins 44, carried by the drive member 40 extend into recesses 58 formed in a drive washer 60 mounted upon one end of a shaft 61. The opposite end of the shaft 61 is rounded as shown at 62 and is provided with a driving element 65. A pilot valve disc 66 is arranged in substantially axial alignment with the shaft 61 and is provided, as best shown in Figure 8, with a pair of blind apertures 67 adapted to receive short pins 68 carried by the driving element 65 and a through aperture 69 adapted to receive a relatively long pin 70. This arrangement has the advantage that it permits the assembly of the parts in only one way. The apertures 67 and 69 are preferably of greater diameter than the pins 68 and 70 to permit slight relative movement of the disc on said pins. Thus, with the rounded end 62 of the shaft 61 engaging the pilot valve disc 66, provision is made for allowing the disc to pivot slightly upon said rounded end to accommodate itself on its associated valve seat. The foregoing pivotal arrangement provides a more or less flexible connection between the pilot valve disc and its driving member whereby any rigid connection between the two which would prevent flush seating of the valve is eliminated.

It will be clear from the foregoing that, as the drive shaft 32 of the clock mechanism rotates the driving member 40, rotation will be imparted to the pilot valve disc 66 through the driven washer 60, shaft 61, and the driving element 65.

The shaft 61, as shown in Figure 2, is packed in the housing 10 by suitable packings 71 and 72. The packing 71 is located above the packing 72 and is engaged by a packing washer 73 which in turn is engaged by a gland 74 threaded into the housing 10 adjacent the drive washer 60. The adjustment of the gland 74 against the washer 73 compresses the packing 71 to the extent desired to form a suitable seal around the shaft 61 to prevent pressure fluid from entering the recess 18. The packing 72 likewise surrounds the shaft 61 and is compressed between packing washers 75 and 76 by a gland member 77 threaded into the housing 10.

A compression spring 78 surrounds the shaft 61 and one end thereof engages the gland 77. The opposite end of said spring engages a seating washer 79 mounted on the shaft 61. The washer 79 is arranged to abut the driving element 65, and, inasmuch as the spring 78 is a compression spring, it tends to urge said driving element toward the pilot valve disc 66. The spring 78 thus urges the rounded end 62 of the shaft 61 against the valve disc 66 to hold the same against its seat at all times, as will appear more fully hereinafter.

Referring again to Figure 8, the master pilot valve disc has opposite flat faces 80 and 81. A

pair of supply ports 82 and 83 extend transversely through the body of the disc and are connected on the side 81 by a pressure fluid supply groove generally indicated by the numeral 86. The master pilot valve disc 66 is also provided with a U-shaped exhaust passageway generally indicated at 87. One leg 88 of said passageway is arranged axially of the pilot valve disc and opens into the side 81 thereof. The other leg 89 of said passageway is spaced radially from the axial leg 88 and also opens onto the side 81 of the pilot valve disc. It will be observed that the supply groove 86 is concentric with the axial opening 88 of the exhaust passage 87 and that it lies identically the same radial distance from said axial opening as the pressure ports 82 and 83 and the leg 89 of said exhaust passageway. The ports 82 and 83 are spaced approximately 120° apart and the leg 89 of the exhaust passageway lies substantially midway therebetween. This spacing, however, is not critical and may be varied if desired.

The side 81 of the pilot valve disc 66 is adapted to seat against a flat surface 95 of a pilot valve seat 96 (see Figure 2). The valve seat 96 is received in a recess 97 formed in the lower end of the housing 10. The valve seat 96 is secured to the housing 10 by a plurality of screws 98 and is provided with an axial port 99 adapted to register with the axial opening 88 in the pilot valve disc 66. The valve seat 96 is also provided with five transverse openings 101, 102, 103, 104 and 105, respectively, which are spaced the same distance from the axis of the valve seat 96 as the pressure supply groove 86 and the exhaust port 89.

A gasket 106 (see Figures 2 and 5) overlies the lower face of the valve seat 96 and the adjacent end surface of the housing 10. A head or closure plate 107 is positioned immediately below the gasket 106, and a series of screws 108 extend through suitable apertures in the housing 10 and gasket 106 into threaded recesses in the head 107 and clamp the gasket between said housing and head in fluid-tight relation.

The gasket 106 is provided with an axial opening 109 aligned with the opening 99 in the valve seat 96 and the port 88 in the valve disc 66. The gasket 106 is also provided with transverse openings 111, 112, 113, 114 and 115, which respectively register with the openings 101, 102, 103, 104 and 105 in the valve seat 96. Thus, it will be clear that the aligned openings in the valve seat 96 and the gasket 106 permit the flow of pressure or exhaust fluid through both of these members simultaneously.

The head 107 is provided with an axial passageway 116 aligned with the passageway 109 in the gasket 106. Said head is further provided with a series of five apertures 121, 122, 123, 124, 125 which are aligned with the aforescribed series of apertures in the gasket 106 and the valve seat 96, respectively.

The head 107 is also provided with an annular depending flange 126, as best shown in Figure 2. This flange is received in the upper end of a supporting pipe 127 which may be of any suitable height. A set screw 128 maintains the housing 10 in assembled relation with the pipe 127.

The lower end of the pipe 127 is threaded into an opening 129 of a T-fitting 128. A pipe 130 is threaded into an opposite opening 131 of said T-fitting and is preferably extended a few feet into the ground to form a rigid support for the fluid distribution control unit C. A pipe 132 is

threaded into the third opening 133 of said T-fitting and is adapted to protect the various tubes extending from the control unit to the various diaphragm valves which will be more fully described hereinafter.

Pressure fluid may be introduced into the control unit C through a pressure tube P. One end of such pressure tube may be connected with the main water supply pipe 6, as diagrammatically illustrated in Figure 1. The opposite end of said tube is received in an opening 135 in the head 107 as shown in Figures 2 and 6. The opening 135 communicates with an L-shaped passageway 136. The gasket 106 is provided with an opening 137 registering with the passage 136, and the housing 10 is provided with a registering passageway 138; the pressure tube P, passage 136, opening 137, and passage 138 all being in communication, whereby fluid under pressure may enter a pressure chamber 139 formed in the housing 10. A strainer plug generally indicated by the numeral 140 is threaded into the chamber 139 as indicated at 141. A gasket 142 is positioned below the head of the plug to form a water-tight seal for the chamber 139.

The strainer plug 140 is shown in detail in Figure 7 and comprises a hollow stem 143 having a series of spaced apart radial flanges 144, 145 and 146 with transverse openings 147 between said flanges communicating with a central opening 148 in said stem. A cylindrical screen 149 surrounds the flanges 144, 145 and 146 and serves to screen the openings 147. The screen 149 is held in place on the plug 140 by suitable wire bands 150.

It will be apparent from the foregoing that pressure fluid must pass through the screen 149 before it can leave the chamber 139 and enter the hollow stem 143. It will be noted at this point that the lower portion of the stem beyond the flange 144 is of greater axial length than the threaded portion 141 of the plug, and that said stem extends into an opening 151 in the housing 10. Thus, the opening 151 will be obstructed by the extremity of the stem 143 until after the threaded portion 141 has been completely backed out of its opening; the object of this arrangement is to permit any water contained in, or flowing into the chamber 139 to flush foreign matter out of said chamber during the removal of the plug rather than carry it into the opening 151.

The opening 151 of the housing 10 communicates with a pressure chamber 66a in which the pilot valve disc 66 is received. This chamber is constantly filled with fluid under pressure for actuation of the various diaphragm valves 1 to 5, inclusive, which control the distribution of water by the system. The packing 72 is provided to prevent the escape of such pressure fluid from the chamber 66a. However, if any leakage past said packing does occur, the same may enter a transverse passageway 155 formed in the housing 10, one end of said passageway being in communication with a space 156a surrounding the shaft 61 and located midway between the packings 71 and 72. The opposite end of said passageway 155 is closed by a screw 156. A vertical passageway 157 extends upwardly from the lower end of the housing 10 and communicates with the passageway 155. The gasket 106 is provided with an aligned passageway 158, and the head 107 is provided with a further communicating passageway 159. Thus, any leakage occurring past the packing 72 may be drained from the housing 10 through the passageways

155 and 157 in the housing, passage 158 in the gasket and the passage 159 in head 107. Any liquid in the passage 159 is free to enter a drain tube B and thus flow from the control unit. It will be understood, of course, that the packing 71 prevents the entrance of fluid into the chamber 18 containing the clock mechanism 17.

Pressure fluid is distributed from the pressure chamber 66a of the control unit C to the respective diaphragm valves 1, 2, 3, 4 and 5 through tubes 1a, 2a, 3a, 4a and 5a as has already been generally indicated. The pressure of the fluid in said chamber is normally sufficient to maintain the pilot disc 66 in engagement with its seat 96. However, in the event that the supply of pressure fluid to said chamber is cut off, the spring 78 will maintain the disc seated and prevent any dirt from getting between said disc and its seat.

Referring now to Figures 2 and 6, it will be seen that the tubing 1a communicates with the passage 121 in the end plate 107 and that the tubes 2a, 3a, 4a and 5a communicate with openings 122, 123, 124 and 125, respectively, in said head 107.

One of the diaphragm valves controlled by the master control device is illustrated in detail in Figures 20 and 21. For convenience, valve 1 of the system has been selected for description. It will be understood that valves 2, 3, 4 and 5 are of similar construction.

The diaphragm valve 1 comprises a valve body 160 provided with an inlet passage 161 and an outlet passage 162. The upper portion of the valve body 160 is provided with an annular surface 163 adapted to support a circular diaphragm 164. A cap 165 is provided with an annular surface 166 adapted to engage the upper peripheral edge portion of the diaphragm 164. The cap 165 and the diaphragm 164 are secured to the valve body 160 by a series of screws 167.

The inlet passage 161 is separated from the outlet passage 162 by a generally vertical partition wall 168. The upper portion of the inlet passageway is defined by a wall 169 having a passage 170 extending therethrough. An annular tapered valve seat 171 surrounds the passage 170 and a central opening 172 is formed in said body above said valve seat.

One side of the flexible diaphragm 164 forms a closure for the central opening 172 and the opposite side of said diaphragm cooperates with the cap 165 to form a side wall of a pressure chamber 173 formed in said cap. A bolt 174 extends through an opening 175 in the diaphragm 164 and has an enlarged flat head 176 in engagement with the upper side of the diaphragm. A cup-shaped member 177 is received in the opening 172 and is also apertured to permit passage of the shank of said bolt therethrough. A renewable disc 178 is nested in said cup-shaped member and is adapted to form a seal with the annular valve seat 171. A nut 179 threaded on the bolt 174 secures the diaphragm 164, cup 177 and disc 178 in assembled relation. The nut 179 has a curved side portion 180 which cooperates with the opening 170 to provide for gradual and quiet cutting off of flow through the valve.

The pressure chamber 173 in the cap member 165 is supplied with pressure fluid through a port 181 and the tube 1a which communicates with the head 107 hereinbefore described. The tube 1a is connected to the cap 165 by a suitable fitting 182. It will be observed that the port 181

opens into the highest portion of pressure chamber 173. This arrangement is important because it prevents trapping of air in said chamber and thereby eliminates chattering of the diaphragm 164 and other noises.

A boss 183 extends centrally upwardly from the cap 165. This boss is internally threaded for the reception of an adjusting stem 184 having a threaded portion 185. The boss 183 is also provided with external threads 186 for cooperation with a gland member 187 adapted to compress suitable packing 188 about the stem 184 to prevent leakage of pressure fluid from the pressure chamber 173.

15 The stem 184 may be adjusted to limit the extent of opening of the valve and the flow therethrough by limiting the upward movement of the flat head 176 and the associated diaphragm 164. In the event that it is desired to maintain a particular valve closed, the stem 184 may be adjusted to preclude opening of the valve altogether.

The diaphragm valve 1 is illustrated in closed position in Figure 20. However, it will be apparent that upon release or exhaust of the pressure fluid from the chamber 173, the pressure of the fluid in the inlet opening 161 will be sufficient to raise the renewable disc 178 from the valve seat 171 and permit a flow of fluid through the opening 170 and into the outlet opening 162 and thence into the service pipe 1.

In the use of the present system, the control knob 30 and its associated pilot valve disc 66 may normally be in the "off" position, as shown in Figure 3 and diagrammatically illustrated in Figure 17. When the control knob is in its "off" position, it is yieldably held against rotation by the engagement of gear tooth 49 in the space 52, as shown in Figure 10, this engagement being maintained by the spring of the clock mechanism 17. When the control knob is in said position, the valve disc 66 is positioned so that the U-shaped passageway 87 is in non-registering relation with the ports 101, 102, 103, 104 and 105. In other words, the valves 1, 2, 3, 4 and 5 at this time will all be subjected to fluid pressure and, therefore, will be closed.

The general operation of the system is as follows:

50 In order to initiate flow through the system, the user may give the control knob 30 one or more turns in a clockwise direction, depending upon the number of times that it is desired to have the sprinkling operation repeated. Figure 55 17 diagrammatically illustrates the relative position of the passages, groove and ports in the pilot valve disc 66 and its seat 96 when the system is inactive. It will be noted from this figure that the pressure groove 86 is positioned to overlie all of the passageways 101 to 105, inclusive, of the valve seat and that, therefore, pressure is applied to the diaphragm valves 1, 2, 3, 4 and 5 to maintain the same in closed position.

Figure 18 shows the passages, groove and ports of Figure 17 in the relative positions that they assume after the clock mechanism has started to drive the pilot disc 66 and to return the control knob 30 in a counter-clockwise direction toward its original position. As shown in this figure, the pressure groove 86 overlies only the passageways 102, 103, 104 and 105 in the valve seat 96 and, therefore, pressure fluid from the pressure chamber 66a in the housing 10 will pass through the supply ports 82 and 83 to said pressure groove, through said passageways in

said valve seat, through the passageways 112, 113, 114 and 115 in the gasket 106, through the passages 122, 123, 124 and 125 in the head 107 and thence through the tubes 2a, 3a, 4a and 5a to the pressure chambers of the respective diaphragm valves 2, 3, 4 and 5 to maintain the same closed. On the other hand, the exhaust groove 87 of the pilot valve disc 66 will have the leg 89 thereof in communication with the passage 101 in the valve seat 96 and consequently relieve the fluid pressure acting on the diaphragm 164 of valve 1 and permit this valve to open by exhausting pressure fluid from the pressure chamber 173 of said valve, port 181, tube 1a, passage 121 in the head 107, passage 111 in the gasket 106, passage 101 in the valve seat 96, through the exhaust passage 87 into the passage 99 of said valve seat, passage 109 of said gasket, passage 119 of said head and finally into the drain tube D. The valve 1 will remain open and the valves 2, 3, 4 and 5 will remain closed until the pilot valve disc 66 has been rotated to such position that the pressure groove 86 is brought into registration with the passage 101 in the valve seat 96. Figure 19 illustrates the pilot valve disc 66 in a position such that the pressure groove 86 has not yet reached the passage 101 and the exhaust passage 87 has not yet been brought into registration with the passage 102 in the valve seat 96. Although the pressure groove 86 is not at this time in registration with the port 102, the pressure acting on diaphragm valve 2 is not relieved and, therefore, this valve is closed and will remain closed until the exhaust passage 87 registers with the passage 102, whereupon said valve will be permitted to open. At the same time that the exhaust passage 87 registers with the passage 102, the pressure groove 86 will be brought into registration with the passage 101 and diaphragm valve 1 will be gradually closed while valve 2 is being opened to effect sprinkling of the area controlled thereby. The opening and closing of the remaining valves occurs successively in a similar manner.

As has been stated hereinbefore, the gearing arrangement shown in Figures 9, 10 and 11 will permit rotation of the control knob 30 through a maximum of substantially three complete revolutions. When the control knob is so turned, the cycle will be repeated three times. Inasmuch as the control knob 30 is returned by the clock mechanism as it actuates the pilot valve disc 66 from one position to another, said knob will indicate through the indicia 38 on plate 20 the particular diaphragm valve which is open and hence the particular area which is being sprinkled. The flow through a given diaphragm valve may be varied or completely cut off by adjusting the stem 184, as previously explained.

Figure 2a illustrates a variation in the construction of the control unit in which the spring 18 is dispensed with and a spring 78a is positioned so that it directly engages and acts upon a pilot disc 66b.

In the variation shown, a driving element 65a is provided with an annular groove 65c adapted to receive one end of the compression spring 78a. The opposite end of said spring presses directly upon the upper face of the pilot disc 66b. A circular member 79b similar to the seating washer 79 is loosely mounted upon the shaft 61b and engages a fixed abutment or shoulder 79c formed in the housing. The drive element 65b is pinned or otherwise secured to the shaft 61b. One of the principal advantages of the aforescribed

construction over that shown in Figure 2 is that the spring 78a is not required to move the shaft 61b downwardly to seat the valve. Fluid under pressure urges the member 79b against the shoulder 79c and does not affect the action of the spring 78a in any way but leaves said spring free to exert its full force on the valve disc 66b to maintain the same seated at all times.

Figures 22 and 23 illustrate a modification of the invention in which the gearing for limiting the number of turns of the control knob has been eliminated and a stop pin 200 has been provided to limit turning of a control knob 30a through substantially one complete revolution. As is shown in Figure 22, a driving member 40a is directly connected to the driven shaft of the clock mechanism 17a and pins 44a are provided to impart rotation to a driven element 60a for driving a shaft 61a to which a pilot disc corresponding to that hereinabove described may be connected.

The modified construction shown in Figures 22 and 23 is relatively simple and may be installed in situations where but a single watering operation is desired. It will be apparent, however, that if a second watering operation is desired, the user need only give the control knob another turn to start the cycle all over again.

While a spring wound clock mechanism has been described as useful in connection with the master control device, it will be understood that other timing mechanism electrically controlled, as by a motor for example, may be employed in lieu thereof. Furthermore, while a sprinkler system has been described in detail, it will be apparent that the present fluid distribution system is adapted for certain industrial uses where flow of fluid may be desired for given time periods and where repeated flow at given time intervals is desired.

It will be also understood that while the invention has been illustrated in embodiments showing their preferred construction, variations therefrom may be developed without departing from the spirit of the invention or the scope of the appended claims.

What I claim is:

1. A sprinkler system comprising, a main supply pipe; a plurality of service pipe lines connected with said supply pipe; at least one sprinkler head connected in each of said service lines; a pressure-operated valve connected in each of said service lines between said main supply pipe and sprinkler head; a master control unit for controlling the opening and closing of said valves; conduit means connecting each of said valves with said master control unit; a conduit connecting said supply pipe with said master control unit; rotatable ported means in said master control unit for controlling the flow of operating fluid through said conduit means; means for manually turning said rotatable ported means in one direction; means for limiting the number of turns that may be manually given to said rotatable ported means; and means for returning said rotatable ported means to its initial position.

2. A fluid distribution system comprising, a fluid supply main; a plurality of service pipe lines connected to said main; a pressure-operated valve connected in each of said service pipes; a master control unit including a housing; a fluid pressure supply conduit connecting said main to said housing; conduit means connecting each of said valves with said housing; a rotatable member within said housing having supply and exhaust ports for successively relieving and applying pressure on

said valves through said conduit means so that said valves open and close in succession and permit fluid from said main to flow through said service pipes; means for manually turning said rotatable member quickly in one direction; means for limiting the number of turns that may be given manually to said rotatable member; and mechanical means for turning said rotatable member relatively slowly in the opposite direction to effect said successive opening and closing of said valves during the return travel of said rotatable member.

3. A fluid distribution system comprising, a main supply pipe; a plurality of service pipe lines connected with said supply pipe; a pressure-operated valve connected in each of said service lines; a master control unit for controlling the opening and closing of said valves; conduit means connecting each of said valves with said master control unit; a conduit connecting said supply pipe with said master control unit; rotatable ported means in said master control unit for controlling the flow through said conduit means; means for manually turning said rotatable ported means in one direction; and means for returning said rotatable ported means to its initial position.

4. A fluid distribution system comprising, a fluid supply main; a plurality of service pipe lines connected to said main; a pressure-operated valve connected in each of said service pipes; a master control unit including a housing; a fluid pressure supply conduit connecting said main to said housing; conduit means connecting each of said valves with said housing; a rotatable member within said housing having supply and exhaust ports for successively relieving and applying pressure on said valves through said conduit means so that said valves open and close in succession and permit fluid from said main to flow through said service pipes; means for manually turning said rotatable member in one direction; and mechanical means for turning said rotatable member relatively slowly in the opposite direction to effect said successive opening and closing of said valves during the return travel of said rotatable member.

5. A sprinkler system comprising, a water supply main; a plurality of service pipe lines connected to said main; at least one sprinkler head connected in each of said service pipes; a pressure-operated valve connected in each of said service pipes between said main and sprinkler heads; a master control unit including a housing; a fluid pressure supply conduit connecting said main to said housing; conduit means connecting each of said valves with said housing; a rotatable member within said housing having supply and exhaust ports for successively relieving and applying pressure on said valves through said conduit means so that said valves open and close in succession and permit fluid from said main to flow through said service pipes; means for manually turning said rotatable member in one direction; and mechanical means for turning said rotatable member relatively slowly in the opposite direction to effect said successive opening and closing of said valves during the return travel of said rotatable member.

6. A sprinkler system comprising, a water supply main; a plurality of service pipe lines connected to said main; a pressure-operated valve connected in each of said service pipes; a master control unit including a housing; a fluid pressure supply conduit connecting said main to said housing; conduit means connecting each of said valves with said housing; a rotatable member within said

housing having supply and exhaust ports for successively relieving and applying pressure on said valves through said conduit means so that said valves open and close in succession and permit fluid from said main to flow through said service pipes; a timing mechanism for driving said rotatable member; and means for manually turning said rotatable member in one direction and simultaneously winding said timing mechanism, said timing mechanism driving said rotatable member slowly in the opposite direction to effect said successive opening and closing of said valves during the return travel of said rotatable member.

7. A sprinkler system comprising, a water supply main; a plurality of sprinkler pipe lines connected to said main; a pressure-operated valve connected in each of said sprinkler pipe lines; a master control unit including a housing; a fluid pressure supply conduit connecting said main to said housing; conduit means connecting each of said valves with said housing; a rotatable member within said housing having supply and exhaust ports for successively relieving and applying pressure on said valves through said conduit means so that said valves open and close in succession and permit fluid from said main to flow in succession to said sprinkler pipe lines; means for manually turning said rotatable member in one direction including a control knob; and timing mechanism for driving said rotatable member slowly in the opposite direction to effect said successive opening and closing of said valves during the return travel of said rotatable member, said timing mechanism being windable by the manual rotation of said control knob.

8. A sprinkler system comprising, a water supply main; a plurality of sprinkler pipe lines connected to said main; a pressure-operated valve connected in each of said sprinkler pipe lines; a master control unit including a housing; a fluid pressure supply conduit connecting said main to said housing; conduit means connecting each of said valves with said housing; a rotatable member within said housing having supply and exhaust ports for successively relieving and applying pressure on said valves through said conduit means so that said valves open and close in succession and permit fluid from said main to flow in succession to said sprinkler pipe lines; means for manually turning said rotatable member in one direction including a control knob; timing mechanism for driving said rotatable member slowly in the opposite direction to effect said successive opening and closing of said valves during the return travel of said rotatable member, said timing mechanism being windable by the manual rotation of said control knob.

9. A device for use in a fluid distribution system comprising, a housing; a head secured to one end of said housing; a pressure chamber in said housing; passageways in said head and housing for conducting pressure fluid to said pressure chamber; a pilot valve disc in said pressure chamber; a shaft for actuating said pilot valve disc; packing means for said shaft; and bleeder passages in said housing and head for draining any pressure fluid from the housing which leaks past said packing.

10. A device for use in a fluid distribution system comprising, a housing having a pressure chamber formed therein, said housing having a passage for admitting fluid under pressure into said pressure chamber; a pilot valve disc in said chamber; a valve seat disposed below said pilot

valve disc; and a head member for said housing disposed below said seat; said pilot valve disc having a pressure supply groove and an exhaust passageway, said seat having a plurality of service passageways positioned to receive pressure fluid from said pressure groove and having a passageway positioned to continuously register with said exhaust passageway, and said head member having passageways registering with the service passageways in said seat.

11. A master control unit for use in a fluid distribution system having a plurality of pressure-operated diaphragm valves comprising, a housing having a pressure chamber formed therein; means for admitting pressure fluid into said pressure chamber; a pilot valve disc in said pressure chamber, said pilot valve disc having pressure ports and a supply groove for controlling the flow of pressure fluid from said pressure chamber; a valve seat for said pilot valve disc having ports in registration with said supply groove in one operative position of said pilot valve disc, whereby pressure fluid may flow through the passageways in said seat to a plurality of pressure-operated diaphragm valves, said valve seat having an axial passageway and said pilot valve disc having an exhaust passageway for successively establishing communication between said axial passageway and said passageways in said valve seat for exhausting pressure fluid from said diaphragm valves when said pilot valve disc is slowly rotated; a clock mechanism driving said pilot valve disc for controlling the duration of the open period of said pressure operated diaphragm valves; and a control knob for winding said clock mechanism.

12. A control unit for a fluid distribution system comprising, a housing; a head secured to one end of said housing; a pressure chamber in said housing; passage means in said head and housing for conducting pressure fluid to said pressure chamber; a strainer in said passage means; a pilot valve disc in said pressure chamber; a shaft for actuating said pilot valve disc; packing means for said shaft; and bleeder passages in said housing and head for draining any pressure fluid from the housing which leaks past said packing.

13. A device for use in a fluid distribution system comprising, a housing having a pressure chamber formed therein, said housing having a passage for admitting fluid under pressure into said pressure chamber; a pilot valve disc in said pressure chamber; a seat for said pilot valve disc in said chamber; a gasket disposed below said seat; a closure member for said housing disposed below said gasket; said pilot valve disc having a pressure supply groove and an axial exhaust passageway, said seat having a plurality of service passageways positioned to receive pressure fluid from said pressure groove and having a passageway positioned to continuously register with said exhaust passageway, and said gasket and said closure member having passageways registering with the service passageways in said seat.

14. A master control unit for use in a fluid distribution system having a plurality of pressure-operated diaphragm valves comprising, a housing having a pressure chamber formed therein; means for admitting pressure fluid into said pressure chamber; a pilot valve disc in said pressure chamber, said pilot valve disc having pressure ports and a supply groove for controlling the flow of pressure fluid from said pressure chamber; a valve seat for said pilot valve disc having pas-

sageways in registration with said supply groove in one operative position of said pilot valve disc, whereby pressure fluid may flow through the passageways in said seat to a plurality of pressure-operated diaphragm valves, said valve seat having an axial passageway and said pilot valve disc having an exhaust passageway for successively establishing communication between said axial passageway and said passageways in said valve seat for exhausting pressure fluid from said diaphragm valves; a clock mechanism in said housing having a shaft for driving said pilot valve disc; and a control knob connected to said shaft for simultaneously winding said clock mechanism and rotating said pilot valve disc to starting position.

15. A control unit comprising, a housing; a casing supported by said housing; said casing containing a clock mechanism including a shaft projecting through the sides of said casing; a knob on one end of said shaft for winding said clock mechanism; a pressure chamber in said housing; a pilot valve disc in said chamber for controlling the distribution of fluid from said chamber; a driving connection between said shaft and said pilot valve disc; a gear fixed relatively to said drive shaft; and an idler gear rotatably supported by said casing and meshing with said first gear, said gears being arranged and constructed to limit the number of turns imparted to said drive shaft by said clock mechanism to correspond to the number of turns through which the knob has been manually rotated in winding said clock mechanism.

16. A drive device comprising, a casing; clock mechanism in said casing; a drive shaft projecting through the sides of said casing; a knob on one end of said shaft for manually winding the clock mechanism, said clock mechanism being arranged so that one winding revolution of said control knob will produce at least one revolution of said drive shaft in the reverse direction; a gear on the opposite end of said shaft; and an idler gear in mesh with said first gear, said gears being arranged and constructed to limit the number of driven turns of said drive shaft to correspond to the number of turns through which the knob has been manually rotated in winding said clock mechanism.

17. A control unit comprising, a housing; a casing supported by said housing, said casing containing a clock mechanism including a shaft projecting through the sides of said casing; a knob on one end of said shaft for winding said clock mechanism; a pressure chamber in said housing; a pilot valve disc in said chamber for controlling the flow of pressure fluid from said chamber; a driving connection between said shaft and said pilot valve disc; a gear fixed relatively to said shaft; and an idler gear meshing with said first gear, one of said gears having a greater number of teeth than the other, and one of said gears having one tooth of greater length than the remaining teeth of said gear and the other of said gears having a plurality of spaces between its teeth deep enough to receive all of the teeth of said first gear and also having a space too shallow to completely receive the long tooth of said first gear, whereby the number of turns through which said shaft and pilot valve disc may be manually rotated is limited.

18. A drive mechanism comprising, a shaft; means for manually rotating said shaft in one direction; mechanical means for rotating said shaft in an opposite direction; a gear fixedly se-

cured on said shaft; and an idler gear meshing with said first-mentioned gear, one of said gears having one tooth of greater length than the remaining teeth of said gear and the other of said gears having a plurality of spaces between its teeth deep enough to receive the teeth of said first gear and also having a plurality of spaces too shallow to completely receive the long tooth of said first gear.

19. A control device for controlling a plurality of hydraulically operated valves in a fluid distribution system comprising, a housing; a plate including a seat secured to said housing, said seat being provided with a central drain passageway and with a plurality of service passageways circularly arranged about said drain passageway, said service passageways being adapted to be placed in communication with the respective hydraulically operated valves; said housing having a pressure chamber formed therein inwardly of said seat and having a passage for admitting pressure fluid into said pressure chamber; a rotatable member in said pressure chamber engaging said seat, said rotatable member being provided with an exhaust passageway having a portion thereof arranged to continuously register with said drain passageway and another portion arranged to successively register with said service passageways when said rotatable member is turned, said rotatable member also having a fluid supply passageway and a supply groove in continuous communication with said pressure chamber, said supply groove being arcuate and disposed in the side of said rotatable member adjacent to said seat, said groove being of sufficient length to register with all of said service passageways when said rotatable member is in a given position; means for manually turning said rotatable member from said given position to another position; and drive mechanism for relatively slowly returning said rotatable member to said given position.

20. A control device for controlling a plurality of hydraulically operated valves in a fluid distribution system comprising, a housing; a plate including a seat secured to said housing, said seat being provided with a central drain passageway and with a plurality of service passageways circularly arranged about said drain passageway, said service passageways being adapted to be placed in communication with the respective hydraulically operated valves; said housing having a pressure chamber formed therein inwardly of said seat and having a passage for admitting pressure fluid into said pressure chamber; a rotatable member in said pressure chamber engaging said seat, said rotatable member being provided with an exhaust passageway having a portion thereof arranged to continuously register with said drain passageway and another portion arranged to successively register with said service passageways when said rotatable member is turned, said rotatable member also having a fluid supply passageway and a supply groove in continuous communication with said pressure chamber, said supply groove being arcuate and disposed in the side of said rotatable member adjacent to said seat, said groove being of sufficient length to register with all of said service passageways when said rotatable member is in a given position; and drive means for turning said rotatable member.

21. A control device for controlling a plurality of hydraulically operated valves in a fluid distribution system comprising, a housing; a plate

including a seat secured to said housing, said seat being provided with a central drain passageway and with a plurality of service passageways circularly arranged about said drain passageway, said service passageways being adapted to be placed in communication with the respective hydraulically operated valves; said housing having a pressure chamber formed therein inwardly of said seat and having a passage for admitting pressure fluid into said pressure chamber; a rotatable member in said pressure chamber engaging said seat, said rotatable member being provided with an exhaust passageway having a portion thereof arranged to continuously register with said drain passageway and another portion arranged to successively register with said service passageways when said rotatable member is turned, said rotatable member also having a fluid supply passageway and a supply groove in continuous communication with said pressure chamber, said supply groove being arcuate and disposed in the side of said rotatable member adjacent to said seat, said groove being of sufficient length to register with all of said service passageways when said rotatable member is in a given position; means for manually turning said rotatable member from said given position to another position including a shaft and a control knob on said shaft; and drive means in said housing for driving said shaft to return said rotatable member to said given position.

22. A control device for controlling a plurality of hydraulically operated valves in a fluid distribution system comprising, a housing; a plate including a seat secured to said housing, said seat being provided with a central drain passageway and with a plurality of service passageways circularly arranged about said drain passageway, said service passageways being adapted to be placed in communication with the respective hydraulically operated valves; said housing having a pressure chamber formed therein inwardly of said seat and having a passage for admitting pressure fluid into said pressure chamber; a rotatable member in said pressure chamber engaging said seat, said rotatable member being provided with an exhaust passageway having a portion thereof arranged to continuously register with said drain passageway and another portion arranged to successively register with said service passageways when said rotatable member is turned, said rotatable member also having a fluid supply passageway and a supply groove in continuous communication with said pressure chamber, said supply groove being arcuate and disposed in the side of said rotatable member adjacent to said seat, said groove being of sufficient length to register with all of said service passageways when said rotatable member is in a given position; means for manually turning said rotatable member from said given position to another position including a shaft and a control knob on said shaft; and drive means in said housing for driving said shaft to return said rotatable member to said given position.

23. A control device for controlling a plurality of hydraulically operated valves in a fluid distribution system comprising, a housing; a plate including a valve seat secured to said housing, said seat being provided with a central drain passageway and with a plurality of service passageways circularly arranged about said drain passageway, said service passageways being adapted to be placed in communication with the respective hydraulically operated valves; said housing having

a pressure chamber formed therein inwardly of said seat and having a passage for admitting pressure fluid into said pressure chamber; a rotatable pilot valve disc in said pressure chamber engaging said seat, said pilot valve disc being provided with an exhaust passageway having a portion thereof arranged to continuously register with said drain passageway and another portion arranged to successively register with said service passageways when said pilot valve disc is turned, said pilot valve disc also having a fluid supply passageway and a supply groove in continuous communication with said pressure chamber, said supply groove being arcuate and disposed in the side of said pilot valve disc adjacent to said seat, said groove being of sufficient length to register with all of said service passageways when said rotatable member is in a given position; means for manually turning said pilot valve disc from said given position to another position including a shaft and a non-rigid connection between said shaft and said pilot valve disc; and drive means for relatively slowly returning said pilot valve disc to said given position.

24. A control device for a fluid distribution system comprising, a housing; a plate including a valve seat secured to said housing, said seat being provided with a central drain passageway and with a plurality of service passageways circularly arranged about said drain passageway; said housing having a pressure chamber formed therein inwardly of said seat and having a passage for admitting pressure fluid into said pressure chamber; a rotatable pilot valve disc in said pressure chamber engaging said seat, said pilot valve disc being provided with an exhaust passageway having a portion thereof arranged to continuously register with said drain passageway and another portion arranged to successively register with said service passageways when said pilot valve disc is turned, said pilot valve disc also having a fluid supply passageway and a supply groove in continuous communication with said pressure chamber, said supply groove being arcuate and disposed in the side of said pilot valve disc adjacent to said seat, said groove being of sufficient length to register with all of said service passageways when said rotatable member is in a given position; a head member secured to said housing below said valve seat, said head member having service passageways communicating with the respective service passageways in said valve seat; a plurality of tubes, each tube having one end connected with a service passageway in said head member and having its opposite end adapted to be connected with a pressure-operated diaphragm valve; and means for turning said pilot valve disc to regulate the flow of fluid through said tubes and hence the opening and closing of said diaphragm valves.

25. A sprinkler system comprising, a main supply pipe; a plurality of service pipe lines connected with said supply pipe; at least one sprinkler head connected in each of said service lines; a pressure operated valve connected in each of said service lines between said main supply pipe and sprinkler head; a master control unit for controlling the opening and closing of said valves; conduit means connecting each of said valves with said master control unit; a conduit connecting said supply pipe with said master control unit; a rotatable pilot disc in said master control unit for controlling the flow through said conduit means; a clock mechanism in said master control unit for rotating said pilot disc; a

knob connected with said clock mechanism arranged to simultaneously wind said clock mechanism and to turn said pilot disc in one direction, said clock mechanism effecting a return of said pilot disc to its initial position; and means for limiting the number of turns that may be manually given to said pilot disc through said knob, said means including a gear connected to rotate with said pilot disc and an idler gear in mesh with said gear, one of said gears having one tooth of greater length than the remaining teeth of said gear and the other of said gears having a plurality of spaces between its teeth deep enough to receive the teeth of said first gear and also having a space too shallow to completely receive the long tooth of said first gear.

26. A fluid distribution system comprising a fluid supply main; a plurality of service pipe lines connected to said main; a pressure operated valve connected in each of said service pipes; a master control unit including a housing; a fluid pressure supply conduit connecting said main to said housing; conduit means connecting each of said valves with said housing; a rotatable ported pilot disc within said housing having supply and exhaust ports for successively relieving and applying pressure on said valves through said conduit means so that said valves open and close in succession and permit fluid from said main to flow through said service pipes; means for manually turning said ported pilot disc in one direction through a plurality of turns; means for limiting the plurality of turns that may be given manually to said rotatable ported pilot disc; and means for turning said rotatable ported pilot disc in the opposite direction to effect said successive opening and closing of said valves during the return travel of said rotatable ported pilot disc.

27. A device for use in a fluid distribution system comprising, a housing having a pressure chamber formed therein, said housing having a passage for admitting fluid under pressure into said pressure chamber; a pilot valve disc in said chamber; a valve seat disposed below said pilot valve disc; and a head member for said housing disposed below said seat; said pilot valve disc having a pressure supply groove and an exhaust passageway, said seat having a plurality of service passageways positioned to receive pressure fluid from said pressure groove and having a passageway positioned to continuously register with said exhaust passageway, and said head member having passageways registering with the exhaust passageway and the service passageways in said seat.

28. A master control unit for use in a fluid distribution system having a plurality of pressure operated valves comprising, a housing having a pressure chamber formed therein; means for admitting pressure fluid into said pressure chamber; a pilot valve disc in said pressure chamber, said pilot valve disc having a plurality of pressure ports for controlling the flow of pressure fluid from said pressure chamber; a valve seat for said pilot valve disc having passageways in registration with said pressure ports in one operative position of said pilot valve disc, whereby pressure fluid may flow through the passageways in said seat to a plurality of pressure-operated valves, said valve seat having an axial passageway and said pilot valve disc having an exhaust passageway for successively establishing communication between said axial passageway and said passageways in said valve seat for exhausting pressure fluid from said valves when said

pilot valve disc is slowly rotated; a clock mechanism driving said pilot valve disc for controlling the duration of the open period of said pressure operated valves; and a control knob for winding said clock mechanism.

29. A master control unit for use in a fluid distribution system having a plurality of pressure operated valves comprising; a housing having a pressure chamber formed therein; means for admitting pressure fluid into said pressure chamber; a pilot valve disc in said pressure chamber, said pilot valve disc having a plurality of pressure ports for controlling the flow of pressure fluid from said pressure chamber; a valve seat for said pilot valve disc having passageways in registration with said pressure ports in one operative position of said pilot valve disc, whereby pressure fluid may flow through the passageways in said seat to a plurality of pressure operated valves, said valve seat having an axial passageway and said pilot valve disc having an exhaust passageway for successively establishing communication between said axial passageway and said passageways in said valve seat for exhausting pressure fluid from said valves; a clock mechanism in said housing having a shaft for driving said pilot valve disc; and a control knob connected to said shaft for simultaneously winding said clock mechanism and rotating said pilot valve disc to starting position.

30. A fluid distribution system comprising, a main supply pipe; a plurality of service pipe lines connected with said supply pipe; a hydraulically operated valve connected in each of said service lines; a master control unit for controlling the opening and closing of said hydraulically operated valves; conduit means for operating fluid connecting each of said hydraulically operated valves with said master control unit; a conduit connecting said supply pipe with said master control unit; a rotatable ported member for controlling the flow of operating fluid through said conduit means; a clock mechanism for rotating said ported member; means connected with said clock mechanism arranged to simultaneously wind said clock mechanism and to turn said rotatable ported member in one direction, said clock mechanism effecting a return of said rotatable ported member to its initial position; and means for limiting the number of winding turns that may be given to said rotatable ported member, said means including a gear connected to rotate with said rotatable ported member and an idler gear in mesh with said gear, one of said gears having one tooth of greater length than the remaining teeth of said gear and the other of said gears having a plurality of spaces between its teeth deep enough to receive the teeth of said first gear and also having a plurality of spaces too shallow to completely receive the long tooth of said first gear.

31. A drive mechanism comprising, a shaft; means for rotating said shaft in one direction; means for rotating said shaft in an opposite direction; a gear fixedly secured to said shaft; and an idler gear meshing with said first-mentioned gear, one of said gears having one tooth of greater length than the remaining teeth of said gear and the other of said gears having a plurality of spaces between its teeth deep enough to receive the teeth of said first gear and also having a plurality of spaces too shallow to completely receive the long tooth of said first gear, one of

said gears also having more teeth than the other of said gears.

32. A drive mechanism comprising, a shaft; means for rotating said shaft in one direction; means for rotating said shaft in an opposite direction; a gear fixedly secured to said shaft; and an idler gear meshing with said first-mentioned gear, one of said gears having one tooth of greater length than the remaining teeth of said gear and the other of said gears having a plurality of spaces between its teeth deep enough to receive the teeth of said first gear and also having a plurality of adjoining spaces too shallow to completely receive the long tooth of said first gear,

15 one of said gears also having more teeth than the other of said gears.

33. A drive mechanism comprising, a shaft; means for rotating said shaft in one direction; means for rotating said shaft in an opposite direction; 20 a gear fixedly secured to said shaft; and an idler gear meshing with said first-mentioned gear, one of said gears having one tooth of greater length than the remaining teeth of said gear and the other of said gears having a plurality of spaces between its teeth deep enough to receive the teeth of said first gear and also having a plurality of spaces too shallow to completely receive the long tooth of said first gear, one of said gears also having more teeth than the other of said gears, said shallow spaces being circumferentially separated in either peripheral direction by at least one relatively deeper space.

34. A drive mechanism comprising, a shaft; means for rotating said shaft in one direction; 35 means for rotating said shaft in an opposite direction; a gear fixedly secured to said shaft; and an idler gear meshing with said first-mentioned gear, one of said gears having one tooth of greater length than the remaining teeth of said gear and the other of said gears having a plurality of spaces between its teeth deep enough to receive the teeth of said first gear and also having a plurality of spaces too shallow to completely receive the long tooth of said first gear, said gear having said long tooth having a total of six teeth and the other of said gears having a total of seven teeth.

35. A fluid distribution system comprising, a main supply pipe; a plurality of service pipe lines connected with said supply pipe; a remotely controlled valve connected in each of said service lines; a master control unit for controlling the opening and closing of said valves; means connecting each of said valves with said master control unit; a rotatable member for controlling the operation of said valves; a clock mechanism for rotating said rotatable member; means connected with said clock mechanism arranged to simultaneously wind said clock mechanism and to turn

60 said rotatable member in one direction, said clock mechanism effecting a return of said rotatable member to its initial position; and means for limiting the number of winding turns that may be given to said rotatable member, said

65 means including a gear connected to rotate with said rotatable member and an idler gear in mesh with said gear, one of said gears having one tooth of greater length than the remaining teeth of said gear and the other of said gears having a plurality of spaces between its teeth deep enough to receive the teeth of said first gear and also having a space too shallow to completely receive the long tooth of said first gear.

DONALD G. GRISWOLD.
